UNITED STATES PATENT OFFICE.

GEORGE F. NOLTE, OF EVANSVILLE, INDIANA.

FIRE-BOX.

No. 858,747.

Specification of Letters Patent.

Patented July 2, 1907.

Application filed November 5, 1906. Serial No. 342,054.

To all whom it may concern:

Be it known that I, GEORGE F. NOLTE, a citizen of the United States, residing at Evansville, in the county of Vanderburgh and State of Indiana, have invented 5 certain new and useful Improvements in Fire-Boxes, of which the following is a full, clear, and exact description, reference being had to the accompanying drawings, forming a part hereof.

My invention has relation to improvements in fire- 10 boxes; and it consists in the novel construction of box more fully set forth in the specification and pointed out in the claims.

In the drawings, Figure 1 is a transverse vertical section on line 1—1 of Fig. 2 of a range showing my invention applied thereto; Fig. 2 is a vertical section at right 15 angles to Fig. 1 on the broken line 2—2 of said Fig. 1; Fig. 3 is an enlarged vertical middle section taken on the line 3—3 of Fig. 4 through one of the perforated nipples which supplies air to the fuel; and Fig. 4 is an 20 end elevation of Fig. 3, with fuel removed.

The present invention is an improvement on one of the structural features of the fire-box forming the subject matter of my pending application for improvement in ranges, Serial Number 315,385, filed May 5, 1906, and 25 has for its object to provide the walls of the fire-box with a series of perforated nipples for supplying jets of air to the fuel, and yet prevent the fuel from banking up against and stopping up the discharge ends of the nipples, all as will better appear from a detailed description 30 of the invention which is as follows:

Referring to the drawings which shows the specific application of the invention to a range, (though it is to be understood that I am not limited thereto as it may be applied to fire-boxes generally) R, represents a 35 range and B the walls of the fire-box, and G, the grate. The walls of the fire-box are spaced a suitable distance from the corresponding walls of the range forming air chambers C from which air may be fed to the fuel through the perforated bosses or nipple n formed on the 40 inner faces of the fire-box walls, and distributed to the best advantage as determined by experience. The nipples are conical in formation and, with the wall of which they form a part are jointly perforated by an inwardly tapering and preferably conical opening or 45 passage p whose discharge end is disposed at an obtuse angle to the axis of the cone so that as shown by the arrows in Fig. 3, the air currents are directed more or less downwardly into the fuel. This downward direc-

tion is furthermore enhanced and insured by the base of the overhanging nose n' which latter subserves the 50 additional purpose of preventing the fuel from banking up against the openings p and choking them up. By reason of this feature a space s is left between the fuel F and the end of the nipple into which the air from the passages p may be directed and discharged. Whatever fuel may rest on top of the nipples will eventually 55 slip down and off the overhanging portion or nose n' as clearly obvious from the drawings. The tapering character of the passage p of course insures a more or less forcible jet of air, having corresponding penetrating 60 powers, so that the number of these nipples may be reduced beyond what would be required were the nipples provided with passages of uniform bore.

Having described my invention, what I claim is:

1. A fire-box wall having a series of nipples projecting 65 beyond the surface of the wall, and jointly perforated therewith, and a formation on the nipple penetrating the fuel and overhanging the discharge end of the perforation.

2. A fire-box wall having a series of nipples projecting beyond the inner surface thereof, and jointly perforated 70 by a passage tapering toward the fire-box, and a formation on the nipple penetrating the fuel and overhanging the discharge end of the perforation.

3. A fire-box wall having a series of conical nipples projecting beyond the inner surface thereof and jointly perforated with said wall by a conical passage tapering toward 75 the fire-box, and a formation on the nipple penetrating the fuel and overhanging the discharge end of the passage.

4. A fire-box wall having a series of conical nipples distributed on the face toward the fire-box, and with said wall jointly perforated by a conical passage converging toward the fire-box, the discharge end of said passage being disposed in a plane making an obtuse angle with the axis of the cone whereby the air currents are directed 85 downwardly, and an overhanging portion penetrating the fuel formed with the nipple and having a bottom wall adapted to insure the deflection of the air currents downward into the fuel.

5. In a fire-box wall an air conducting nipple of conical 90 contour formed on the wall, and provided with a passage tapering toward the apex of the cone and truncated in a plane making an obtuse angle with the axis of the cone, and a formation on the cone projecting beyond or overhanging the discharge end of the passage and penetrating 95 the fuel.

In testimony whereof I affix my signature, in presence of two witnesses.

GEORGE F. NOLTE.
